COVERING CONSTRUCTION

John A. Topping, Bronxville, N. Y.

Application June 21, 1934, Serial No. 731,579

3 Claims. (Cl. 108—7)

This invention relates to coverings and covering constructions particularly those constructions utilizing elements laid upon a surface in overlapping arrangement. The invention more especially relates to the construction of roof coverings or coverings upon surfaces exposed to the weather.

Covering elements in the form of strips and used in the construction of roofs or to form a weather tight covering are well known in many forms. Such roofing elements have been made with a plurality of tabs separated by recesses, which recesses in some cases are similar to or complementary to the tabs or in other cases, are different from the tabs in shape. Such elements have been laid in overlapping arrangements to produce by the cooperation of the outlines of the edges of the elements, designs of different character. For example, strips having tabs formed as one-half of a hexagon and with a recess between the tabs of similar shape may be laid in such a way as to complete the hexagon motif in the roof construction. Also strips having a sinusoidal outline of the edge thereof may be laid with the tabs tangent to the inner lines of the spaces between the tabs of a subjacent strip, thereby to form a symmetrical motif in the roof. Other elements or strips with different form of outline for the edge to be exposed of the strip have been laid in overlapping arrangement with the tabs lapped upon and bearing upon a portion of the surface of the underlying or subjacent element or strip.

The present invention is concerned with the constructive a covering or of a roof utilizing elements of the type just described and in various forms having generally a recess between tabs, which recess may be like or similar to or complementary to the adjacent tabs or may be different therefrom. The elements, however, which I utilize according to my invention have between the tabs a recess of substantial proportions more particularly with respect to the width thereof, that is, the dimension in the direction of the course in which the elements are placed. In laying such elements heretofore, more or less regular or symmetrical designs have been obtained by the arrangement of elements with respect to each other and particularly the arrangement of one course of elements with respect to another.

Also as the tabs usually bear merely upon the flat surface of the element overlapped by the tab and more particularly when the upper face of the elements is surfaced with granular mineral

material, as is common in roofing materials and roofing elements, the tab may be insecurely held down upon the subjacent element so that it may easily be blown up in the wind or in some cases may more readily curl up under the action of heat and the weather. Especially when elements surfaced with granular material are used it is difficult to secure a bond between the rear or under face of the element and the grit surfaced upper face of the subjacent element. Not only does the grit or mineral surfacing material afford a surface to which the overlying element does not readily adhere but the under face of the element is usually covered with a layer of talc or mica which prevents the bituminous coating and impregnating materials on the under face of the element from coming in contact with the upper face of the subjacent element.

It is an object, therefore, of my invention to provide a construction utilizing covering elements or strips having tabs with recesses therebetween and laid in such relation to each other, and particularly one course with respect to the subjacent course, that the tabs may be formed or may become formed after laying in such a way as to resist the curling action of the weather and the tendency of the wind to blow up the tab.

It is a further object of my invention so to construct the roof or covering that the adhesive bituminous materials commonly utilized to impregnate and coat covering materials exposed to the weather may have opportunity to contact with the upper face of a subjacent or underlying element thereby to secure a bond which will assist in preventing the tabs from blowing up and also will assist in preventing the water from being driven up between the tab and the underlying element or between portions of two superimposed elements.

A further object of my invention is to provide an element or strip of such form and construction that the bituminous materials carried by the element or strip may be permitted to bleed or exude from the element or strip so as to act as adhesive between two superimposed strips.

In order to accomplish the objects of my invention I may utilize ordinary strips of covering or roof materials having tabs with spaces therebetween, preferably of substantial extent with respect to the tabs, and may lay these strips in overlapping arrangement in courses with the tabs of a superimposed strip extending over and bending or sagging down into the space or re-

cess between the tabs of a strip in a subjacent course. Depending upon the particular form of the tab and of the recess over which the tab is to extend the amount of the overlap or extension over the recess may vary. With a tab of relatively wide form as compared with the recess over which it is to extend, the amount of the extension may be greater in order to secure a sufficient sag of the material of the overlapping tab into the space or recess between the two tabs of a subjacent strip. The amount of this sag preferably should be sufficient to bring the tab into contact with the upper face of the second strip below which is exposed between the two tabs of the subjacent strip over the recess of which the tab of the first strip extends.

While in general my invention may find its widest application with strips or roofing elements which have tabs of similar or like form to the recess therebetween, the invention is not limited alone to such form of strips and constructions made thereof but may apply to any strips or other elements and constructions utilizing such strips or elements, which permit the sagging or bending down of the tab into the space or recess between two tabs of a subjacent strip to bring the under face, or in some cases only the edge portion, of the tab of the first strip into contact with said exposed face of the third strip or element. It will be understood from the above explanation that not only may the tab be so formed as to bring the under face of the tab or its edge into contact with the upper face of the element in the third course of three overlapping courses, but the tab may be so preformed, or it may be so deformed after laying, that a portion thereof sags or bends or is fitted down into the space between two tabs of a subjacent element. This form of the tab not only produces a more rigid tab but is of such form that the wind cannot so easily lift it and blow it up as is commonly experienced with tabs of flat form laid in the ordinary overlapping arrangement.

Moreover, particularly with roofing elements having bituminous or asphaltic materials impregnating the body thereof or which are coated with such materials, the edge of the tab, particularly as it tends to bleed under heat, such as the heat of the sun, after laying upon the surface or roof structure, brings adhesive material into contact with the exposed face of the third course. Also, these adhesive materials may be brought into contact with the asphaltic or bituminous material bleeding from the edge of the second course beneath or into contact with said edge itself, to cohere therewith or adhere thereto and provide a bond between the several elements in the several courses. Thus, further prevention of the curling action of the weather and the tendency of the wind to blow up the tabs is insured. In the particular form of the element which is part of my invention hereafter to be described in connection with the drawings, this action is assisted and a more secure and efficient bond is made possible by the particular treatment and form of the under surface of the element.

In addition to the structural advantages obtained by the particular construction of the roof utilizing elements in overlapping arrangement in courses as described above, I may also produce novel design effects with elements of standard or common form, which designs are the result of the mechanical arrangement of the elements and the relation of the extension of the tabs over the

spaces or recesses between the tabs of a subjacent element.

My invention further contemplates the process of producing elements which have the under face thereof so formed as to assist the bleeding of the asphaltic or bituminous materials therefrom and into contact with the face of an element exposed between two adjacent tabs of a subjacent element. In carrying out this process I may utilize the process described in the patent to Outman No. 1,426,497 in order to remove from the under-face of the elements or from the sheet from which they are being made the coating material usually applied thereto to seal the under face. I may, however, either remove this coating material by other methods, such as by the use of solvents, or I may prevent the application of this coating upon the particular portions of the strip, or of the sheet from which the strip is being made, which will insure that the tabs or at least the edge portions of the tabs are subjected to this treatment in order to permit the bleeding or exuding of the adhesive asphaltic or bituminous materials. In some cases, however, I may apply adhesives of particular character to these portions of the sheet or of the tabs in order to secure the desired adhesive character when the strips are laid in a roof or covering construction. Moreover, in some cases I may merely omit from these areas of the sheet or of the strip the talc or mica commonly applied to the coating upon the under face of the covering elements or strips to prevent them sticking to other strips in a package when being handled or shipped. Other features of the invention and advantages to be obtained thereby will appear from the following description of the drawings in which

Figure 1 shows an element of the type utilized in my invention;

Figure 2 shows an assembly of such elements in the manner of the invention;

Figure 3 is a cross section on line 3—3 of Figure 2;

Figure 4 shows an assembly in the manner of the invention of a different type of element;

Figure 5 shows a method of producing one of the forms of elements utilized in my invention;

Figure 6 shows a modified method of producing a form of the elements utilized in my invention.

Figure 7 is a section as on line 7—7 of Figure 6.

Figure 8 is a section as on line 8—8 of Figure 6.

Figure 1 shows an element 1 having a generally sinusoidal edge outline providing upon the element tabs 2 with spaces or recesses 3 therebetween. In this particular form of the element the recesses 3 are of generally similar shape to the tabs 2 and are of similar dimensions to those of the tab. The recesses, therefore, provide a space of substantial extent over which the tab may extend or overlap, as shown in Figure 2. It will be noted from Figure 2 that a substantial portion of the tab 2 laps upon the recess 3. In the particular embodiment of the invention shown in Figures 1 and 2 this is accomplished by virtue of the width of the recess with respect to the width of the tab. By suitably forming the under surface of the tab 2 or providing a coating of adhesive character thereon the tab 2 may be caused to adhere to the surface 5 of an element 1 in the second course below that of the element having the overlapping tab. Moreover, the edge 7 of the tab for a considerable part of its length overlies the surface 5 of said

subjacent element and may be brought into contact therewith as well as with the edge 9 of the recess 3 where these edges intersect or cross. As will be more clearly understood from the description to follow in connection with Figures 5 and 6, means may be provided for increasing the capacity of the tab 2 to adhere to the surface 5. It will be clear, however, from Figure 2, and by reference to the section shown in Figure 10, 3, that the edge portion of a tab 2 of an element A in one course may be bent down or may sag or may be deformed so as to bring the portion of the tab 2 extending over the recess 3 of an element B in the next subjacent course into contact with the surface 5 of an element C in the second subjacent course. Thus the underside of the tab 2 may bear against and be caused to adhere to the surface 5 of the element C and the edge 7 of the tab 2 may be brought into contact with the surface 5 so that the adhesive or asphaltic materials exuding from the tab along the edge 7 may act to bind the tab 2 to the surface 5. It also will be clear that at the points of intersection or crossing of the edge portion 7 of the tabs 2 with the inner edge 9 of the recesses 3 the adhesive or asphaltic material exuding from these two edges may cohere or bond together, thus acting to hold the tab 2 down to the subjacent element and to prevent curling or blowing 30 up of the tab by the wind.

While the above description has been directed to the form of element having an edge to be exposed of generally sinusoidal outline and the features and functions of the various parts described are provided by the element shown in Figure 1, other forms and arrangements of the elements may be used. For example, the element, when provided, as shown in Figure 1, with circular notches 10 may be laid with a greater amount of 40 overlap or extension of the tabs 2 over the recesses 3 than that shown in Figure 2 so that the notches 10 on two adjacent elements may become generally superimposed and with the edges of said adjacent notches intersecting or interlocking. Thus a still greater extent of the edge 7 of the tab 2 may be brought into contact with the surface 5 of the second subjacent element. An increased extent of the edge 7 in contact with said surface 5 will provide for a greater amount of the adhesive or asphaltic material 50 exuding or bleeding from said edge 7 to contact with the surface 5 and to secure adhesive bond thereto.

In Figure 4 is shown a further modification of the invention in which elements having tabs 20 of V shape are laid with the edge portions or point 22 overlapping the inner portion 24 of the V shaped recess 28 between the tabs 20. The edge 22 may intersect or cross the edge 24 and the edge 22 may contact with the surface 28 of an element in the second course below in the manner described in connection with the elements of Figures 2 and 3. The tabs may thus become deformed or may sag down into the recesses 26 and may be adhesively bound to the surfaces 28 in the manner described in connection with Figures 1, 2 and 3. Figure 3 also may be considered as typical of the cross section of Figure 4.

In Figure 5 is shown a method of producing upon a strip or element of the type utilized in my invention a surface on the under side of the tab of a character to provide or assist in securing the adhesive bond of the tab to the surface exposed by the recess of a subjacent course overlapped by the tab. Upon a roofing sheet 30 of

sufficient width to permit two elements to be cut therefrom with the coursewise dimension of the elements extending lengthwise of the sheet I may apply to the central portion of the area of the sheet a band 32 of adhesive material extending lengthwise of the sheet. The dimension of this band 32 of adhesive transversely of its length or transversely of the sheet may be sufficient to cover the tabs 2 or a substantial part of the area of the tabs of the two strips. Preferably at least 10 the portion of the tabs 2 adjacent the outer edge 7 of the tab is coated with the adhesive material.

In the particular embodiment illustrated in Figure 5 elements 1 of generally sinusoidal outline may be cut from the sheet 30 by cutting said sheet 30 in sinusoidal outline within the width of the band 32. Thus two elements 1 may be produced from the sheet 30, which elements will have tabs with recesses therebetween, the tabs of the elements being similar and of like 20 dimensions to the recesses. It will be apparent from consideration of Figure 5 that the tabs will have upon their area, which may be the area of the under face of the tab, a coating of the adhesive material of the band 32. It, therefore, 25 will be understood that when the tabs 2 are bent down or sag into the recesses 3 in the manner described in connection with Figures 1, 2 and 3 that the adhesive upon the under face of the tab may be brought into contact with the surface 30 5 of the second subjacent course and the tab may thus become bound to said surface and prevented from curling up or blowing up when exposed to the weather.

In Figure 6 is shown a modification of the 35 method of providing upon the tabs a surface with adhesive character. In this embodiment of the invention the sheet 30 may be coated in two parallel bands 40 and 42 with adhesive material of a character utilized in the band 32 to secure 40 adhesive bond of the tab to the surface 5. The bands 40 and 42 of adhesive material may be of such width and may be so spaced apart transversely of their length as to provide upon a substantial portion or a desired portion of the end 45 surface of the tab a coating of adhesive when the sheet 30 is cut in an outline, such as the sinusoidal outline, to form elements having tabs and recesses therebetween in the manner described above. It will be apparent from a consideration of Figure 6 that the tabs on both elements may have applied thereto the adhesive coating if the sinusoidal outline is cut in the sheet 30 so that the portions of said outline forming the outer edges of the tabs lie within 50 the bands 40 and 42 of adhesive material applied on sheet 30.

Instead of applying continuous bands 40 and 42 to the sheet 30 these bands may be applied as discontinuous bands having sections or portions 60 46 and 48 spaced along the sheet 30 in the direction of its length distances equivalent generally to the spacing of the tabs as cut from the sheet 30 by the sinusoidal outline. If the adhesive material is thus applied to the sheet a 65 saving in adhesive material necessary to secure the desired result is effected while providing upon the tabs 2 adjacent the edge 7 thereof the adhesive coating. Moreover, it will be clear by consideration of Figure 6, together with the description above in connection with Figures 1, 2 and 3, that the inner edge portion 9 of the recess 3 between the tabs will have upon the under face of the element some of the adhesive coating so that where the edges 7 and 9 intersect in an 70 75

assembly of the elements 1, as shown in Figure 3, the adhesive material upon the tab or exuding or bleeding therefrom may contact with the adhesive material upon the recess or bleeding 5 or exuding therefrom, in order to cohere therewith and secure the adhesive bond desired to hold the tab and prevent its blowing or curling up.

While in connection with Figures 5 and 6 the 10 adhesive character of the under side of the element has been described as secured by the application of adhesive material to the sheet 30 and the subsequent cutting of the sheet within or in relation to the band or bands of applied 15 adhesive material, within the scope of the invention this adhesive material may be applied to the sheet after cutting the sinusoidal or other outline in such relation to said outline as to secure application of adhesive to the tabs. The application 20 of the adhesive to the tabs also may be accomplished by applying the adhesive to elements which have been severed and separated from the sheet, which application may be made by hand or by any convenient means.

25 As referred to above, I may utilize the process described in the patent to Outman No. 1,426,497 in order to secure the adhesive character for the under face of the tabs. Instead of applying adhesive in the band 32 of Figure 5 or in the 30 bands 40 and 42 of Figure 6, I may scrape, according to the process of Outman, the coating applied upon the under face of a roofing sheet to remove from said face or to reduce the thickness of the applied coating. Thus, in bands 35 53 and 55 corresponding to bands 32 and 40 and 42, as shown in Figure 7 I may leave exposed, or, as shown in Fig. 8, with only a residual coating 51 thereon, the structure of the felt base or other base 50 of the roofing material which is usually 40 impregnated with bituminous saturant or other material of adhesive quality. By cutting the sheet in the manner described in connection with Figures 5 and 6 with respect to the bands formed by thus scraping the sheet, the scraped areas 45 53 or 55 become formed upon the tabs 2. When these scraped areas contact with the surface 5 of the second subjacent element and when, under the action of heat or of the sun the bituminous materials exude or bleed from the 50 base structure, which action is made possible by removal of the sealing coating normally applied upon the under face of the roofing material to prevent such action, adhesive bond may be secured between the tab and the surface 5 to hold 55 the tab securely thereto. The bleeding or exuding of the adhesive or saturant material from the edges 7 and 9 of the elements as above described, may take place in the same manner as when the adhesive is applied to the bands 32, 60 40 and 42. This bleeding or exuding of the saturant material may occur because in cutting the sheet to form the edge of the element the base structure saturated with the adhesive or saturant becomes exposed.

65 As shown in Figures 2 and 4 means may be provided in the well known manner for gauging one element with respect to an element in a subjacent course to insure the correct amount of exposure. This gauging also will insure the proper 70 relation of the tabs 2 to the recesses 3 and the degree to which they extend over the recesses. This gauging means may be provided, as shown in Figure 1, by an offset portion 12 at one end of the element and a corresponding extension

14 at the other end of the element formed respectively with edges 13 and 15 which may be used to gauge with the rear or overlapped edge 16 of an element in a subjacent course.

While the invention has been described above 5 in connection with elements having tabs like or similar to the recesses therebetween, the invention is not limited to elements of this type and may be applied to elements having recesses which are unlike the tabs but which are of such form 10 that the tab may be caused to bend down into the recess of a subjacent element or may be permitted to sag into said recess under the action of heat or of the sun or under other action or force. The invention also includes elements in 15 which the tabs, whether of like or similar form to the form of the recess, or whether the tabs and recesses are of unlike form, are shaped or formed or molded with a portion thereof depressed or bent down so as to provide a form 20 which will fit into or may fall into the space provided by the recess. Such formed, deformed or molded tabs may, because of the form thereof, be sufficiently stiff to resist the curling action of the weather and the tendency of the wind to 25 blow up the tabs in an assembly of the elements upon the structure. Various other modifications, which may be made while following the methods and utilizing the forms of elements described above, lie within the scope of the invention. 30

Having thus described my invention, I claim:

1. A covering element of flexible sheet material for laying in overlapping arrangement in courses with similar elements, said element having the portion thereof to be exposed formed 35 with tabs extending from the body thereof separated by recesses therebetween, said tabs and said recesses being of such form that the tab on a superposed element may be bent down into the recess of an element in the subjacent course, 40 said tabs having a mastic adhesive exposed upon the under face thereof to bind said tabs to the surface exposed by said recesses of the course beneath, a sealing coating for said mastic adhesive being sufficiently reduced where said tabs overlap said recesses to permit bleeding of said adhesive from said flexible sheet material. 45

2. A covering element comprising an absorbent flexible base impregnated with a mastic material, and a coating upon the under face of said base 50 for sealing said mastic impregnating material in said base, said coating upon a portion of said under face of said base being of a thickness sufficiently reduced to permit said mastic impregnating material to bleed from said base and 55 to bind said element to the surface on which it bears.

3. A covering construction comprising a plurality of covering elements formed of flexible base material with tabs separated by recesses 60 therebetween, said base material being impregnated with a mastic adhesive and said elements being laid in courses in overlapping arrangement and with a tab of one course extending over a recess of the subjacent course, the under face of 65 each element having a mastic coating applied thereto to seal the mastic adhesive impregnating the base material, said mastic coating at least upon the portions of the tabs which overlap the recess being of sufficiently reduced thickness to 70 permit said mastic adhesive to bleed from said sheet.

JOHN A. TOPPING.
